UNITED STATES PATENT OFFICE

2,460,753

SPRING EQUIPPED DOUBLE CONE TIE

Stephen J. Kardos, Allentown, Pa.

Application April 17, 1945, Serial No. 588,867

2 Claims. (Cl. 242—130)

1

This invention relates to knitting machines and has for its principal object to provide means whereby production is materially increased, much time is saved, accuracy of work assured and the nerves of knitters relieved.

Another object of the invention is to provide means for carrying two cones of yarn (or one and a half cones) upon a common cone supporting plate of a knitting machine.

A further object of the invention is to provide means whereby two cones of yarn may be supported one above the other upon a common holder.

Other features and advantages will become more readily apparent from the following description and the accompanying illustrative drawings in which:

Figure 1 is a sectional elevation of a pair of cones of yarn embracing my invention.

Figure 2 is an elevational view of my yarn cone holder.

Figure 3 is a sectional elevational view taken on line 3—3 of Figure 1, and

Figure 4 is an elevational view of a modification.

In the accompanying drawings as above enumerated and in the following specification, like characters of reference indicate like parts throughout and in which 10, indicates my two cone supporting member which comprises a bar 11, consisting of a cylindrical bar flaring to larger diameter at its upper end 12. The lower end 13, of the bar 11 is provided with a vertical bore 14, adapted to seat upon the upper end 15, of a common cone support 16, which is secured to the yarn plate 17, of a knitting machine by means of a nut 18, threaded on the reduced lower end 19, of said support. A set screw 20, threaded through the transverse bore 21, is adapted to hold the members 11 and 16, in fixed relation.

Above the solid central portion 22, of bar 11, is another vertical bore 23, provided with an outwardly flaring terminal end 24, in said upper end 12. The said flared end to bore 23, forms a guide for the lower terminal 25, of an elongated pin or rod 26, the upper end 27, of which is fixedly secured in the bore 28, of a solid conical block 29, of a size to fit into the lower portion 30, of a commercial cone 31, upon which cotton yarn is usually wound for use in knitting machines.

The said end 27, of pin or rod 26, is provided with an indentation 32, into which the rounded end 33, of a pin 34, projects through a bore 35, in the upper end 36, of bar 11. This pin is at-

2

tached to the end 37, of a strong leaf spring 38, secured at 39, to the bar 11, whereby when the pin or rod 26 is rotated, the pin 34 will drop into the indentation 32, and pin or rod 26 will be held against rotation.

The block 29, is provided in its under side 40, with a conical enlargement 41, of the bore 28, to receive the tip 42, of a lower cone 43.

In Figure 4, of the drawings, I show a modification of the invention in which the member 44, has fixed in its lower end 45, a plug 46, provided with a threaded bore 47, into which a bolt 48, is threaded, whereby the device is secured to a plate 17, thus eliminating the cone support 16, commonly carried on the yarn plate, in which case the lower cone 43, is entirely supported by my device.

As knitting machines carry as many as sixty-four or more cones of yarn, and one knitter (operator) usually has to tend three or four of the machines and if one cone of yarn gives out, the goods being manufactured is damaged, thus it is a great strain on the nerves of the knitter to keep watch on all of the cones of yarn. With my device in use a great deal of such worry is eliminated and damaged goods lessened and stoppage of the machines for changing cones lessened to a very considerable extent as when a cone is run down to about half, a full cone may be set under it in the usual manner and it will take only a moment or two to change from top to bottom cone. By referring to Figure 1 of the drawings, it will be seen that when the cotton on the cone 31 has been partially used, the cone 31 may be removed and a new or unused cone 43 will be forced down over the pin or rod 26 to pass through an opening in the top of the cone, until the bottom of the cone rests upon the yarn plate 17. The cone 31 will then be replaced upon the pin or rod 26 to assume the position as shown in Figure 1. By having a full cone near the cone being used, the time for replacing a full cone for an expended one will be reduced to a minimum. What is very important is that there will at all times be a full cone and a full and a part full cone on each yarn table or support and the danger of damaged goods through the yarn on any table giving out is obviated.

It is thought that persons skilled in the art to which the invention relates will be able to obtain a clear understanding of the invention after considering the description in connection with the drawings. Therefore, a more lengthy description is regarded as unnecessary.

55 Minor changes in shape, size and rearrange-

ment of details and parts such as come within the purview of the invention claimed may be resorted to, in actual practice, if desired.

Having now described my invention that which I claim as new and desire to procure by Letters Patent is:

1. In combination with a plate for a knitting machine and a bobbin supporting bar therefor, said bar being formed with axially aligned sockets in its upper and lower ends, the upper end of said bar being enlarged and centrally countersunk, a spindle insertable in said lower socket for locking the bar on said plate, a bobbin supporting spindle in the upper socket in said bar, a bobbin on said spindle, said bar being formed with a radial opening communicating with the upper socket, and a leaf spring supported locking detent on said bar disposable through said radial opening for locking said bobbin supporting spindle in said upper bore.

10

20

2. The combination as claimed in claim 1, and means for supporting the bobbin being used and a reserve bobbin in juxtaposition upon said bobbin supporting spindle with said reserve bobbin contacting said plate and said bobbin being used contacting the upper end of said reserve bobbin.

STEPHEN J. KARDOS.
